UNITED STATES PATENT OFFICE.

HANS MUMM, OF LIDGERWOOD, NORTH DAKOTA.

GRAIN-SHOCKER.

1,217,332.

Specification of Letters Patent. Patented Feb. 27, 1917.

Application filed December 6, 1915. Serial No. 65,341.

To all whom it may concern:

Be it known that I, HANS MUMM, a citizen of the United States, residing at Lidgerwood, in the county of Richland and State 5 of North Dakota, have invented certain new and useful Improvements in Grain-Shockers, of which the following is a specification, reference being had to the accompanying drawings.

This invention relates to harvesting mechanism, and particularly to machines for shocking grain.

The primary object of my invention is the provision of a very simple, easily operated, and effective mechanism adapted to be attached to and moved with a binder on the field, whereby sheaves may be received from the binder platform and whereby these sheaves or bundles may be formed into a shock, the shock then deposited upon the ground butt downward.

A further object of my invention is to provide a shock former composed of resilient elements curved approximately into the 25 form of the shock, there being means provided whereby the resilient elements may expand as the sheaves are deposited therein and whereby these elements may be compressed to compress the sheaves into the 30 form of a compact shock and whereby the shock former may be turned into a vertical position to drop the sheaves and at the same time opened or expanded so as to permit the shock to drop out.

A further object of the invention is to so construct the former that it may expand 35 equally and not take a flattened or elliptical form in expanding as the sheaves are deposited within it.

A further object of the invention is to provide means for automatically feeding the sheaves into the former by power derived from the traction wheels of the machine, to provide means whereby the shock 45 compressing the former expanding and the tipping of the former to a discharge position and the return of the former to its receiving position may be accomplished through the power of the traction wheels, 50 the mechanism being thrown into operative engagement with the traction wheels by means of a hand trip for this purpose under the control of the operator.

A further object of the invention is to 55 provide means to prevent the tipping of the former while sheaves are being dis-

charged into the former, and still another object is to provide means for adjusting the former so that it will be disposed in a vertical discharging position whether the 60 machine is moving up and down hills or operating on side hills, this mechanism being automatic in its action.

Other objects will appear in the course of the following description.

My invention is illustrated in the accompanying drawings, wherein:

Figure 1 is a plan view of the shock former showing its dumping position on dotted lines;

Fig. 2 is a rear elevation of the former;

Fig. 3 is a side elevation thereof;

Fig. 4 is a transverse sectional view;

Fig. 5 is a perspective view of the shipper rod 50 and shipper lever;

Fig. 6 is a perspective view of the annulus 55;

Fig. 7 is a perspective view of the means for equalizing the expansion of the former;

Fig. 8 is a side elevation of the packing 80 forks and operating mechanism;

Fig. 9 is a fragmentary perspective view showing one of the packer forks and its connection to the operating crank;

Fig. 10 is a detail sectional view of a 85 portion of the mechanism for operating the packer arms;

Fig. 11 is a cross sectional view of the rail 11 showing the bearings 21 in elevation but broken away;

Fig. 12 is a side elevation of the cam 85 for stopping the rotation of sleeve 72;

Fig. 13 is a diagrammatic side elevation of the machine to show the mechanism whereby the former is leveled in going up 95 or down hills;

Figs. 14 and 15 are like views to Fig. 13, entirely diagrammatic in form, however, Fig. 14 showing the operation of the mechanism in Fig. 13 when the machine is ascending a hill, and Fig. 15 showing the same mechanism operating when the machine is descending a hill;

Fig. 14^a is a fragmentary top plan view of the means for steadyng and retracting 105 the rod 93;

Fig. 16 is a top plan view of the means for holding the rod 93 from accidental operation;

Fig. 17 is a perspective view of the mech- 110 anism for leveling the former upon side hills;

Fig. 18 is a side elevation of the mechanism shown in Fig. 17;

Fig. 19 is a like view to Fig. 18, but showing the former in its lowered and dumping position;

Fig. 20 is a side elevation of the rail 11, showing the means for holding the two sections of the rail in alignment;

Fig. 21 is a top plan view of the rail 11, showing the pivotal connection of the two sections of the rail;

Fig. 22 is a transverse section of a preferable form of rail, this view also showing in section the boxing 21^a.

Referring to these drawings, it will be seen that my mechanism includes a rectangular frame composed of the side bars 2 upon the rear ends of which are mounted the traction wheels 3. The rear ends of these side bars are connected by a transversely extending beam 4 forming part of the frame. The extension beyond the side bars 2 and at the other side of the machine is connected to a longitudinally extending frame bar 5 which is formed at its rear extremity with an eye 6 whereby it may be operatively connected to a binder. Formed upon this bar 5 is an upwardly extending arm 7 having a forwardly extending portion 8 which is parallel to but above the frame bar 5 and extends beyond the eye 6. Formed upon one of the frame bars 2 is an upwardly extending member 9 corresponding to the member 8 but which also extends inward as well as upward. Pivoted to the extremity of the bars 8 and 9 are the rails 10 and 11. The rails are pivoted to the bars 8 and 9 at 12 and extend forward beyond these pivotal points as at 13.

Disposed between the rails is the former A. This former includes oppositely disposed parallel rods 14 and 14^a. To the rod 14 are attached a plurality of arcuate resilient arms or rods 15 illustrated as four in number. To the rod 14^a is attached a plurality of resilient arms or rods 16 illustrated as four in number, the upper ends of these rods crossing the upper ends of the rods or arms 15. The lower ends of these rods beyond their point of attachment to the member 14^a are extended downward and laterally in a curve and below and spaced from the depending ends of the rods 15 and project out beyond these rods in position to receive the sheaves as they are discharged from the binder. The members 16 are also connected to each other by means of a longitudinally extending rod 17 and the members 15 are connected to each other by means of the longitudinally extending rod 18. These rods 14, 14^a, 17 and 18 hold the members 15 and 16 in spaced relation but do not interfere with their resilience.

Attached to the rods 14^a and projecting laterally therefrom is a shaft or axle 19

which is relatively short, while attached to the rod 14 and extending laterally therefrom is a shaft or axle 20 which is relatively long. It will be noted that the former composed of the rods 15 and 16 is 70 disposed relatively close to the rail 11 and separated more widely from the rail 10. The shaft 19 is rotatably mounted in a boxing or journal bearing 21 which is slidably mounted upon the rail 11 but held from 75 lateral movement with relation thereto. Surrounding the shaft 20 is a sleeve 22 which is in turn slidably mounted in a boxing 23 which has sliding engagement with the rail 10 but no lateral movement relative 80 to the rail, the boxings 21 and 23 following the rail. Thus if the rails are bent inward the corresponding boxing will move inward when it reaches that part of the rail, while if the rail is bent outward the corresponding boxing will move outward when it reaches that part of the rail. The reason for this movement will be hereafter stated.

Mounted upon the shaft 19 and extending upward therefrom is a standard 24 and 90 mounted upon the shaft 20 and extending upward therefrom is the corresponding standard 25. Mounted upon the upper ends of these standards are the bell crank levers 26. Mounted upon the upper end of the standard 24 is a tubular member 27 and mounted upon the upper end of the standard 25 is a rod 28 which telescopes within the tubular member 27. From one of the bell crank levers 26 a wire or other flexible connection 29 extends to the upper end of the standard 24, and from the other end of the same bell crank lever a wire or flexible connection 30 extends to the rod 17 about midway of its length. From the upper end of the other bell crank lever 26 a like cord or flexible connection 29 extends to the opposite standard, while from the other end of the same bell crank lever a flexible connection 30 extends to the rod 18. The purpose 100 of these bell crank levers 26, the connections extending therefrom, and the telescopic members 27 and 28 is to cause an equal expansion of the arcuate members 15 and 16 as the former is filled with sheaves. The operation of these members will be more fully described later on. Generally speaking, the operation of the parts heretofore described is as follows: At a predetermined time after the former has been filled, the former is 110 moved forward on the rails. It will be noted that the rail 10 is formed with the inwardly extending portion 31 and that the rail extends parallel to the axis of the binder for a certain distance, as at 32, and 120 is then outwardly bent as at 33. The rail 11, however, has only one bend 33^a which corresponds to the bend 33. Now when the former moves forward under the action of the mechanism which will be later described, 125 130

the boxing 23 is engaged by the bend 31 and forced inward. This causes the compression of the former and compresses the sheaves contained therein. As the boxings 21 and 23 together with the former move still farther forward the boxings 21 and 23 engage the bends 33^a and 33, respectively, and are drawn away from each other, thus expanding the former. At this time the rails 10 and 11 are tilted from a horizontal to a vertical position by a mechanism which will be later described, and the shock is dropped upon the ground. After the shock has been disengaged the rails are again tilted to a vertical position, releasing the shock and disposing the former in position to again receive the sheaves.

Mounted upon the rear end of the frame formed by the members 2 and 5 is a main shaft 34 which carries the cranks 35 and 36. These cranks are connected by rods 37 and 38, respectively, to the boxings 21 and 23, respectively, and therefore a complete rotation of the shaft 34 will cause the former 25 to move forward its full stroke and then cause the retraction of the former to its normal position. The shaft 34 carries at its extremity the loose sprocket wheel 39, there being a sprocket chain 40 connecting it to a sprocket wheel 41 mounted upon a packer driving shaft 42. This packer shaft carries at its end the gear wheel 43 which meshes with a gear wheel 44 mounted upon a shaft 45 which operates certain packing 35 arms as will be later described.

Mounted upon the shaft 34 is a sprocket wheel 46 which is loose upon the shaft 34 and is driven by means of a sprocket chain 47 from the axle 48 upon which the traction 40 wheels are mounted. This sprocket chain 47, however, may be connected to receive power from the traction wheels in any suitable manner. One end of the sprocket wheel 46 is formed with clutch teeth, and coacting with these clutch teeth is a clutch member 49 slideable upon the shaft 34 but keyed or splined thereto. This clutch member is moved into engagement with the sprocket wheel 46 by means of a shipper rod 50, this rod being in turn connected to a shipper lever 51 mounted upon a bracket 52 on the frame 4. The lower extremity of this shipper lever 51 has attached to it a rod 53 which extends laterally into position to be operated by the binder operator, or this rod 53 might be automatically operated by a trip wheel or other suitable mechanism not shown. The clutch member 49 is urged out of engagement with the sprocket wheel 46 by means of a spring 54 and the member 49 is held in engagement with this sprocket wheel by means of a split ring or annulus 55 which is disposed concentric to the shaft 34 and is supported in any suitable manner, this ring 65 having parallel guides 56 engaging with a

pin 57 on the member 49. When the member 49 is moved inward into engagement with the sprocket wheel 46 the pin 57 will move out from between the guides 56 which form stops to the arms, and when the member 49 commences to rotate the pin 57 will pass the opening between the members 56 and as a consequence the annulus 55 will prevent the spring 54 from returning the clutch 49 to its disengaged position until 70 the clutch has made one revolution and the pin 57 has again come back to the entrance of the slot between the members 55. Thus the clutch 49 will be held in engagement with the sprocket wheel for one complete 75 revolution and power will be communicated from the traction wheels of the machine to the shaft 34 during this complete revolution. Thus during this complete revolution the cranks 35 and 36 will move the former forward to its discharging position and then 80 85 retract it to its receiving position.

For the purpose of tipping the rails 10 and 11 upon their pivots 12 to thus cause the rails to take an inclined position in order to discharge the shock near to the ground, I mount upon the shaft 34 the elliptical gear wheel 58 which in turn engages with an elliptical gear wheel 59 mounted upon a crank shaft 60 supported in a standard 90 95 100 105 110 115 120 125 130 61 or in any other suitable manner. It will be seen that these gear wheels are rotatably mounted each at one of its foci and it will be seen that by reason of using these elliptical gear wheels the speed with which they relatively rotate will be varied and the rotation of one of the gear wheels will be relatively rapid at one point and relatively slow at another. At the time that the clutch 49 is thrown in the gear wheels will be in the position shown in Fig. 3, and will start at their slowest speed. While at the time that the members 22 and 19 are at the bends 33 and 33^a the shaft 60 will be rotating at its highest speed. The crank 61^a on the shaft 60 is connected by means of a rod 62 with a yoke 63 whose two arms extend to a point in front of the former and then extend laterally and forward and are pivotally connected as at 64 to the rear ends of the rails 10 and 11 respectively, rearward of their pivotal points. It will thus be seen that at the time that the former has been forced forward so that the members 21 and 23 are at the bends 33 and 33^a the rails are suddenly tipped from their horizontal position to an inclined position, and simultaneously the members 21 and 23 move outward under the action of the bends 33^a and 33, respectively, thus expanding the former and permitting the shock to drop out. The yoke 63 then moves rearward bringing the rails to a horizontal position and the former moves back to its normal or receiving position ready for filling.

Thus the operation of setting down the shock on the ground is completed during revolution of the main shaft 34, and on the completion of this one revolution of the 5 main shaft 34 the clutch 49 will automatically slide back out of its engagement with the sprocket wheel 46 and the shaft will be held from any further rotation by the pin 57 engaging between the members 56. This 10 prevents any accidental movement of the shaft 34 and holds the former in its receiving position.

The packing mechanism is as follows: The packing shaft 45 is formed with a plurality 15 of cranks 65, each of these cranks carrying sleeves 66 through which passes the shank or arm 67 of a packer. These arms 67 have outwardly divergent tines 68 at their outer ends and at their inner ends are pivoted as 20 at 69 to a link 70 in turn pivoted to the frame bar 5. These packers move between and on each side of the lateral extensions 16^a of the rods 16 and act to force the bundles of grain as they are received from the binder 25 into the shock former. The packer shaft 45 is operated from the packer driving shaft 42 and the manner in which this shaft is operated is as follows: Connected to rotate with the loose sprocket wheel 39 and mounted 30 upon the shaft 34 is a sleeve 72, which sleeve carries upon it the cam shaped member 73 having clutch teeth 74 which engage with clutch teeth on the sprocket wheel 46 but which are normally held out of engagement 35 therewith. The cam member 73 has a collar 75 formed with an annular groove and engaging this annular groove is an annulus 76 in turn connected to a yoke 77, this yoke in turn being attached to a rod 78 which extends parallel to the shaft 34 and passes 40 through an eye 79 formed in the upper end of the shipper rod 50. This rod 78 is formed with two stops 80 and 81 disposed on each side of the eye 79. The purpose of this rod 45 78 and its stops will be later stated.

The cam member 73 is normally urged toward the sprocket wheel 46 by means of a spring 82. The cam member is normally held away from its clutched engagement 50 with the sprocket 46 by means of a stop 83. When, however, the cam member turns in one direction the shoulder or highest point 84 of the cam will pass the stop and as a consequence the spring 82 will then act to force 55 the cam and the clutch toward the sprocket wheel 46 and force the sleeve 72 into engagement with the sprocket wheel to thus cause the rotation of the sleeve and of the gear wheel 39. This of course will cause a rotation of the shaft 42, the shaft 45, and the operation of the packers. This initial sliding rotation of the sleeve 72 in order to allow the highest part 84 of the cam to pass the stop 83 is secured by the fact that the binder 60 pushes a bundle against the packer tines 68,

and this pushing of a bundle against these packer tines will cause a slight rotation of the shaft 45 and of the shaft 42. This will be transmitted to the sleeve 72 which will turn the cam 73 just sufficient to cause its 70 highest point 84 to pass the stop 83, whereupon the spring will throw the clutch members on the sprocket wheel and the cam into engagement with each other. When the cam 73 is in clutched engagement with the 75 sprocket wheel 46 the sleeve 72 will make one complete revolution, or until the edge of the cam by its engagement with the member 83 has forced the cam back out of its engagement with the sprocket wheel. At 80 this time the cam plate 85 which is mounted upon the sleeve 72 will contact with the spring 86 which is mounted in any suitable manner and which holds the sleeve 72 from any further accidental rotation until the 85 sleeve is again actuated by the pressure of a bundle on the packer tines 68. While the shock former is in operation, however, that is, to complete the shock, expand, dump the shock and return to its original position, the 90 packer tines 68 are turned back below the rod 68^a by the engagement of a slidably mounted plate 87 with an arm 88 which prevents a rotation of the sleeve 72 which will release the cam 73. This plate 87 is mounted in guides 89 supported in any suitable manner upon the frame of the machine and is shifted by means of a rod 90 connected to the upper end of the lever 51. When, therefore, the lever 51 is moved by means of the 95 connection 53 to shift the clutch 49 into engagement with the sprocket wheel 46 the slide 87 will be shifted to the left in Fig. 1, and will be in position to engage the arm 88 and prevent any rotation of the sleeve 72. 100 Immediately, however, that the clutch 49 flies back under the action of the spring the slide 87 will be moved out of the way of the arm 88.

In order that the shock shall be discharged 110 from the former it is necessary that at the time that the rails are tipped downward the former should be rotated through approximately 90° so as to carry the forward end of the former downward toward the ground. 115 As will be noted, the shaft 19 is freely rotatable with relation to the boxings or bearings 21 and 23 and therefore it is necessary to provide means for positively rotating this shaft and rotating the former with the shaft 120 as the boxings 21 and 23 move forward under the action of the cranks 35 and 36. To this end I mount upon the shaft 19 the arm 91 connected by a link 92 to a rod 93 extending to the front of the machine. A joint 125 breaking arm or strut 94 is also rigidly connected to arm 91 at an angle of approximately 45°. The free end of this arm is crotched or bifurcated, as at 95, to engage with arm 93 for a purpose which will be 130

later stated. With this construction, as the shaft 19 moves forward under the action of the cranks 35 and 36 the rods 91, 92 and 93 will move from the position shown in full lines in Fig. 13, thus rotating the shaft 19 as illustrated in dotted lines in Fig. 13 to a position where the shock may be discharged.

It will be obvious that means must be provided for discharging the shocks in a vertical position both when the machine is moving up or down a hill and when the machine is operating on a side hill. Unless this means is provided the shock will be discharged at an angle to the vertical. When the machine is moving down hill and the shock former is moved to a dumping position, the shock former comprising the members 13 and 16 must be tilted to such a position that the axis of the shock is at an obtuse angle to the plane of the forward portion of the machine, and when on the other hand the machine is moving up hill the shock former must be tilted to a position where its axis is at an acute angle to the plane of the machine.

The mechanism now to be described operates to increase the tilting movement of the shock former in one place to an amount greater than its normal tilting movement and decrease it in the other case to an amount less than its normal tilting movement. To this end, at the rear of the machine there is mounted a standard 96 supporting at its upper end the pivoted balance bar 97 having a downwardly extending finger 98 disposed immediately beneath the pivot and extending radially relative thereto. Also pivotally mounted upon the standard 96 is an arm 100 carrying a yoke 101. Pivotally mounted upon the ends of the yoke are the bell crank levers 102 and 103. The upwardly extending arms of both bell cranks are connected to the rod 93. The finger 98 normally extends downwardly in a plane immediately between the arms of the yoke, as illustrated in Fig. 13, but the lower end of the finger when the former is in its receiving position is disposed above the plane of the horizontal arms of the bell cranks.

Below the arm 100 is a cam 104 which is mounted upon the shaft 30 which reciprocates the bearings or boxings 21 and 23. When the former starts to move forward and the links and rods 91, 92 and 94 initially start to rotate the shaft 19, the cam 104 engages the arm 100 and lifts the yoke 101 upward. If the machine is on level ground the balance bar 97 will be parallel to the arms of the bell cranks 102 and 103 and the finger 98 will be disposed between the ends of the bell crank. When the arm 100 rises therefore under the action of the cam, the finger will pass between the arms of the bell cranks and will not affect these bell

cranks and a normal rotation of the shock former will be secured. When the machine is moving up hill, however, as illustrated in Fig. 14, the finger 98 will be disposed over the arm of bell crank 102 and when the yoke rises under the action of the cam the finger will engage the bell crank and tilt it in a direction to shift the rod 93 rearward, which, through the link 92 and the arm 91 will rotate shaft 19 sufficiently less than its normal amount of rotation so that the axis of the shock will be at an acute angle to the plane of the machine. On the other hand, when the machine is running down hill the finger 98 will engage with the bell crank 103 which will increase the movement of the shaft 19 to an amount greater than 90° and the former will be held at an obtuse angle to the plane of the machine. In other words, the action of the shock leveling device illustrated in Fig. 13 is to in one case increase the angular movement of the shock former and in the other case decrease such angular movement.

While the rod 93 might be connected directly to the arm 91, such a connection would not give sufficient rotation to the shaft 19 and further would cause the arm 91 to move to a dead center when the rod 93 was in either of its extended positions. By providing the link 92 and providing the crotched arm 94, I secure a much greater angular movement of the arm 91 and obviate the dead-centering of this arm 91. As the rod 93 moves forward, the arm 91 will move upward and the arm 94 will move downward, but on a reverse movement of the rod 93 the arm 91 will move downward, the arm 94 will engage at the joint of the rod 93 to the link 92 and will cause the link 92 to take an angular relation to the rod 93 and the force applied by the rod 93 will be applied to the arm 94 to rotate the shaft.

Preferably and in order to prevent the rod 93 and the link 92 from dropping downward when the link 92 and the rod 93 are in alignment with each other, I pivotally connect the rod 93 to the link 92, as at 105, and provide the finger 106 which is attached to the link 92 and extends over the joint 115 and is adapted to engage with the rod 93 and prevent any descent of the link 92 and rod 93 at the joint, as shown clearly in Fig. 14.

The rod 93 must be held from any undue forward or rearward movement which would tend to cause the shock former to oscillate accidentally, and to this end I mount upon an arm 107 extending from the rear end of the machine parallel to the rod 93 a yoke 108 the ends of which are bifurcated or formed with seats 109. Attached to the rod 93 and projecting laterally out therefrom is an arm 110 which normally rests upon both of the seats 109. A spring 130

111 acts to draw the arm 110 against the seat 109. Now, movement of the rod 93 either forward or rearward from this normal position will tend to expand the spring 5 111. The rearward movement of the rod 93 will lift the arm 110 from the inner seat 109 and cause the arm to fulcrum upon the outer seat 109 which will expand the spring. A forward movement of the rod 93, 10 however, will cause the rod to bear upon the inner seat 109, raise it from the outer seat and thus expand the spring. Thus this spring 111 will yieldingly resist any accidental longitudinal movement of the rod 15 93 and therefore resist any accidental rotation of the shaft 19 and of the former thereon.

The mechanism for causing the shock former to be disposed in a vertical position 20 when the machine is running along the side hill operates on the same principle as the parts 97 to 104. As will be seen, the rail 11 is in two sections *a* and *b*, the joint of this rail being designated 113. The hinged 25 connection of the two sections is disposed to one side of the rail by the formation of laterally projecting arms hinged to each other, as at 114 (see Fig. 21), and this is done so as to permit the bearing or boxing 30 21 to move over this joint with ease. Because of the hinged joint in the rail the section *a* can move to a greater amount or farther than the section *b*. Thus when the rail 11 is tilted to a position to discharge 35 the shock the lower end or section of the rail can move to a greater or less angle to the horizontal than the upper section of the rail. A spring arranged as will be later described, yieldingly holds both sections of 40 the rail in alinement so that both sections will normally rise together. Under normal circumstances, when the rails 10 and 11 are tilted by the yoke 63 and the allied parts 45 the two sections *a* and *b* of the rail will have the same angle and be in alinement with each other as seen in Fig. 13. When, 50 however, the machine is running over a side hill, the level adjusting means now to be described will cause the section *a* to either be accelerated or retarded in relation to the section *b*.

In order to cause this acceleration or retardation of the movement of the section *a* of the rail 11, I mount upon an upward 55 extension 115 of the support 9 an arm 116 upon which the balance bar 117 is pivotally mounted. This balance bar has the downwardly depending finger 118 disposed radially upon the axis of the balance bar. 60 Extending laterally from the rail 11 rearward of its joint 113 is an arm 119 carrying at its extremity a yoke 120. To the ends of this yoke are pivoted the levers 121 and 122. The lever 121 is pivoted intermediate its ends, while the lever 122 is

pivoted at one end. Attached to the section *a* of the rail forward of its joint and of its pivot is a forwardly extending arm 123 to the extremity of which the lever 121 is connected by a link 124, the link being attached 70 to the outer end of the lever. A link 125 connects the inner end of the lever 122 to the end of the arm 123.

If now the machine is operating on a side hill which causes the traction wheels 3 75 to be raised above the level of the harvesting machine, the balance bar will cause the finger 118 to be disposed over the lever 121. Now when the rails are tipped to an inclined position by the action of the yoke 63 80 the rail 11 forward of its point of pivotal connection to the arm 9 will rise, and the rail rearward of its pivot will move downward. Under normal circumstances and when the machine is operating on the level, 85 the rise of the forward end of the rail will carry the yoke 120 upward and the finger of the balance bar will pass between the ends of the bell crank levers 121 and 122, but if operating on the side hill inclined 90 downward from the traction wheel 3, the rise of the forward end of the rail 11 will carry the lever 121 against the finger of the balance bar, actuating or depressing the lever 121 and thereby raising the arm 123, 95 which, as it is connected to the rail section *a*, will cause the relatively upward movement of the rearward section *a* of the rail. This causes the section *a* to be disposed at an angle to the section *b* so that when section *a* of the rail is at an angle of 45° to horizontal the section *a* will be at a greater angle. The rail 10 will of course have executed the same movement as the rail section *b* and therefore the rail section *a* will 100 be at a greater angle to the horizontal than the rail 10 and this will allow that side of the shaft 19 toward the hill to slip down lower than the boxing or bearing 23 to cause the former to be disposed in a vertical position. If the inclination of the hill is such that the traction wheels are disposed lower than the harvester side of the machine, then the finger on the balance bar will engage lever 122 and as a consequence 110 the section *a* of the rail will be retarded in its movement relative to the section *b* of the rail and relative to the rail 10 and the rail 10 will move farther than the rail section *a* and as a consequence the boxing or 115 bearing 23 will shift downward below the boxing or bearing 21.

The mechanism used for the purpose of supporting the rail sections *a* and *b* yieldingly in alinement with each other under 120 ordinary circumstances is illustrated best in Fig. 20, and is analogous to the means for holding the rod 93 from vibration. The rail section *b* has extending from it adjacent the joint an arm 126 which is rigid with the rail. 125

The rail section *a* has extending from it an arm 127 and an extension 128 pivoted to it. This extension may move outward, that is, away from the arm 126, but cannot move inward beyond a position in alignment with the arm 27 by reason of the stop 129 which is attached to the section 128 and extends over the joint between the sections 127 and 128. Attached to the arm 126 and extending at right angles thereto is a stop member 130 and connecting the arm 126 to the extension 127 and arm 128 is a coiled contractile spring 131. The operation of this is that when the rail section *a* is bent downwardly with relation to the section *b* the arms 126 and 127 are bent into converging relation but the extension 128 will strike the stop 130 and be forced outward, thereby thus expanding the spring as illustrated in Fig. 20. When, however, the rail section *a* is turned upward or outward with relation to the rail section *b* then the arm 127 and the arm 126 are turned into diverging relation. The extension 128, however, is held from any movement and also shifted into a divergent relation to the arm 126 when the spring 131 is expanded. Thus the spring 131 normally acts to hold the sections *a* and *b* in alignment with each other but permits the yielding movement in either direction.

In Figs. 1 to 20, for the sake of simplicity and to avoid confusion, I have illustrated the bearings 21 and 23 as being in the form of boxings embracing a single rail 11. In actual practice, however, this construction would prevent the easy movement of the boxings or bearings upon the rail and therefore I preferably form the rails in three sections, as illustrated in Fig. 22. Only one of these rails has been shown in these sectional views, the rail 11. These three sections comprise the base member 132 and the two angular members 133 and 134, these angular members being spaced above the base member and also spaced from each other, the boxing which is designated in this case 21^a resting upon the base member 132 of the rail to slide therealong and is held from lateral movement and is guided by the members or sections 133 and 134, the boxing having an upwardly extending pin 135 which engages between the members 133 and 134. Thus the boxing is held firmly supported but is guided by the rails.

The general operation of my mechanism is believed to be obvious from the description heretofore. The former, comprising the rods 15 and 16, when it receives the bundles of grain, is in the position shown in Fig. 4 and in full lines in Fig. 1. In this position the former is expanded and the packing members 67 are being operated across the bundles of grain into the former. When the former is filled the operator pulls

upon the rod 53. This engages the clutch member 49 into engagement with the clutch member 46 and at the same time disengages packer shaft 42 from operative engagement with the sprocket wheel 46. The cranks 35 and 36 now push the former forward upon the rails 10 and 11 and this acts to compress the shock former so as to shape the shock and then as the sliding boxings 21 and 23 raise the laterally expanded portions of the rails the former expands laterally so that the shock may be freed when the former is rotated to a dumping position. As the former is moving toward the rear ends of the rails 10 and 11 the rod 93 will exert a pull upon the link 92 and the arm 94 and the former will be rotated in the direction of the arrow, Fig. 13, from the position shown in full lines to the position shown in dotted lines and the shock 85 will be deposited upon the ground. As soon as the shock is discharged the rails are tipped back to their horizontal position and at the same time the boxings or bearings 21 and 23 are drawn forward on the rails to the position shown in Fig. 1 and this action of course causes the former to tilt back to its original receiving position. As the former moves toward the forward ends of the rails the bearing boxings 21 and 23 will move laterally to expand the former to its receiving position. The bell cranks 26 with the connections 29 and 30 act to cause the rods or bars 15 and 16 to expand uniformly and not merely laterally. The mechanism as shown in Figs. 13 to 15 and 17 to 20 will cause the shock always to be deposited in a vertical position without regard to the lateral or longitudinal inclination of the ground.

Having thus described the invention, what is claimed is:

1. In a shock forming machine, two laterally disposed opposite sets of arms bowed in opposite directions, the upper ends of the arms being free and extending upward and toward each other, the arms of one set being disposed in staggered relation to the arms of the other set and the arms crossing each other adjacent their upper ends, the sets of arms being relatively bodily movable toward or from each other and one set of arms extending below the lower ends of the other set in spaced relation thereto and extending laterally beyond the lower ends of said other set to form means for supporting and receiving a shock, and means for relatively shifting the sets of arms bodily toward or from each other in a horizontal plane to expand and contract the former.

2. In a shock forming machine, a pair of supporting rails, a frame formed of two laterally disposed sections, each mounted upon one of said rails, the sections being movable toward or from each other, and

- oppositely disposed sets of curved arms, each mounted upon one of said sections, and movable with said sections, one set of arms being extended beneath and laterally beyond the 5 other set of arms and in spaced relation thereto to provide means for supporting and receiving the shocks, and means for shifting said frame sections toward or from each other to carry the shock former arms toward 10 or from each other.
3. In a shock former, oppositely disposed parallel rails, sliding members movable along the rails, longitudinally extending bars operatively supported upon said sliding 15 members, oppositely disposed sets of curved resilient arms mounted upon said bars intermediate their ends, the arms intersecting each other at their upper ends, the rails being formed to cause contraction and expansion of the arms as the sliding members move 20 along the rails, vertically disposed standards attached to said bars, bell cranks mounted upon the upper ends of the standards, and flexible connections extending from the 25 upper end of each standard to the opposite bell crank, a flexible connection from the said bell crank to the corresponding set of arms.
4. In a shock former, a supporting frame, 30 oppositely disposed rails pivoted at their forward ends to said frame, a former slidably and rotatably mounted on the rails, positively operating means for sliding the former toward the free ends of the rails and 35 then tipping the former to a discharging position and returning the former to a receiving position after it has been discharged, and positively operating means for tilting the rails downward when the former nears 40 the free end of the rails and then lifting the rails to their initial position after the former has been discharged.
5. In a shock former, a supporting frame, rails pivoted at their forward ends to said 45 frame, a former proper comprising a frame formed of oppositely disposed sections, each section being slidably and rotatably mounted upon one of said rails, the sections being mounted for bodily movement toward 50 or from each other, oppositely disposed sets of curved members, each set being mounted upon one of said sections, and movable with the sections toward or from each other, means for sliding the former toward the free 55 ends of the rails, means for forcing the oppositely disposed sections of the former frame toward each other as they move toward the free ends of the rails, and then moving them away from each other, and 60 means for simultaneously tipping the rails and former to discharge the shock.
6. In a shocking machine, a supporting frame, parallel rails pivotally mounted upon the frame, a shock former comprising oppositely disposed sections rotatably and slid-

ably mounted upon the rails, the sections being movable toward or from each other, oppositely disposed sets of curved arms rigidly mounted upon said sections intermediate the ends of the arms, the upper ends 70 of the arms extending upward and toward each other and intersecting, and being transversely movable relative to each other, the lower ends of one set of arms extending below and laterally beyond the other set of 75 arms to provide means for receiving bundles, the resilient arms and the frame sections extending laterally as the sheaves are fed thereto, means for shifting the former longitudinally along the rails and simultaneously 80 causing a movement of the frame sections toward each other to thereby cause a compression of the shock, means for tipping the rails and simultaneously rotating the former in a vertical position, and means for expanding 85 the former to discharge the shock.

7. In a shocking machine, a supporting frame, oppositely disposed parallel rails pivotally mounted upon the frame at their forward ends, bearings slidably mounted 90 upon the rails, a former comprising a supporting frame formed in two sections, each section having a shaft extending through the corresponding bearing, the oppositely disposed sections being connected for unitary 95 movement along the rails, said connection permitting the frame sections to move toward or from each other, two sets of oppositely disposed curved resilient arms mounted upon the frame sections of the former, the arms of one set extending beneath and beyond the lower ends of the arms of the other set, means for feeding material 100 on to the extended arms, means for shifting the former rearward on the rails, and simultaneously causing the frame sections of the former to move toward each other, and then move away from each other, means for 105 simultaneously tipping the rails, and means for rotating the former to a discharging position.

8. In a shocking machine, oppositely disposed rails, both of said rails at their rear ends being outwardly offset, one of said rails intermediate its ends being inwardly 110 offset, bearings slidably mounted upon the rails, a tubular member slidably mounted on that bearing which engages with the rail having the intermediately disposed inward offset, trunnions mounted upon the shock 115 former and extending one into the said tubular member and the other into the opposite bearing, means for shifting the bearings longitudinally along the rails to thereby cause the contraction and final expansion of the former, means for tipping the rails, and means for rotating the former to a shock discharging position.

9. In a shocking machine, a supporting frame, rails pivotally mounted thereon, a 120

- shock former slidably and rotatably mounted upon the rails, feeding devices extending parallel to the shock former when in its normal position, a traction wheel shaft, a main shaft disposed at the forward end of the machine, manually operable means for engaging the traction wheel shaft with the main shaft, cranks on the main shaft operatively connected with the bearings, a counter shaft, a crank thereon operatively connected with the forward ends of the pivoted rails, gearing on said main shaft adapted to operate said crank, mechanism operating to tip the former as it moves forward under the operation of the first named cranks, and means for automatically causing the operative engagement of the main shaft with said feeding devices upon a complete revolution of the main shaft.
10. In a shocking machine, a supporting frame, oppositely disposed rails pivotally mounted on the supporting frame, bearings slidingly mounted on the rails, a former pivotally mounted in said bearings and movable therewith, feeding devices disposed parallel to the rails, a traction wheel shaft mounted at the forward end of the machine, a sliding sprocket wheel loosely mounted upon the main shaft and having oppositely disposed clutch teeth and engaged with said traction wheel, a clutch on the main shaft manually shiftable into engagement with one end of the sprocket wheel, cranks on the main shaft operatively engaging with the sliding bearings, a counter shaft, a crank thereon operatively engaging with the forward ends of the rails to cause a tipping of the rails upon a rotation of the crank, elliptical gear wheels mounted upon the counter shaft and the main shaft to actuate said crank, means for causing the rotation of the shock former upon a forward movement of the bearings, a feed operating shaft operating said feeding devices and extending parallel to the main shaft, and a clutch operatively engaged with said feed operating shaft and mounted loosely upon the main shaft, and automatic means for throwing the first named clutch of the main shaft out of engagement with the sprocket wheel and throwing the last named clutch into engagement with the sprocket wheel upon one complete rotation of the main shaft.
11. In a shocking machine, a supporting frame, a traction wheel on one side of the frame, means on the other side of the frame whereby the frame may be attached to a harvester, oppositely disposed rails pivotally mounted upon the frame, bearings slidably mounted on the said rails, a shock former rotatably mounted on the bearings, a main shaft disposed at the forward end of the machine, a sprocket wheel having oppositely disposed clutch teeth loosely mounted upon the main shaft and constantly driven from said traction wheel, a clutch mounted on the main shaft and operably engageable with one end of the traction wheel, a sleeve rotatably mounted upon the main shaft, a clutch carried by said sleeve and operably engageable with the other end of the traction wheel, cranks on the main shaft, connections from said cranks to the sliding bearings on the rails, a counter crank shaft, a yoke connected to the forward ends of the rails operatively connected between the yoke and the crank shaft, elliptical gears mounted one on the crank shaft and one on the main shaft to cause the rotation of the crank shaft, means causing the tipping of the shock former upon the forward movement of said sliding bearings and the former, a longitudinally extending feed shaft, arms mounted thereon and adapted to cast material into the former, a feed operating shaft extending parallel to the main shaft and operatively engaging with said feed shaft, means for operatively engaging said sleeve with the feed operating shaft, manually operable means for throwing the first-named clutch into engagement with the sprocket wheel, means for holding said clutch into engagement during one revolution of the sprocket wheel and then releasing the clutch, and means then operating to throw the clutch on the sleeve into engagement with the sprocket wheel to thereby cause the actuation of the feed operating shaft and feed shaft.
12. In a shocking machine, a supporting frame, a traction wheel on one side of the frame, means on the other side of the frame whereby the frame may be attached to a harvester, oppositely disposed rails pivotally mounted upon the frame, bearings slidingly mounted on the said rails, a shock former rotatably mounted on the bearings, a main shaft disposed at the forward end of the machine, a sprocket wheel having oppositely disposed clutch teeth loosely mounted upon the main shaft and constantly driven from said traction wheel, a clutch mounted on the main shaft and operably engageable with one end of the traction wheel, a sleeve rotatably mounted upon the main shaft, a clutch carried by said sleeve and operably engageable with the other end of the traction wheel, cranks on the main shaft, connections from said cranks to the sliding bearings on the rails, a counter crank shaft, a yoke connected to the forward ends of the rails operatively connected between the yoke and the crank shaft, elliptical gears mounted one on the crank shaft and one on the main shaft to cause the rotation of the crank shaft, means causing the tipping of the shock former upon the forward movement of said sliding bearings and the former, a longitudinally extending feed shaft, arms mounted thereon and adapted to cast material into the former, a feed operating shaft extending parallel to the main shaft and operatively engaging with said feed shaft, means for operatively engaging said sleeve with the feed operating shaft, manually operable means for throwing the first-named clutch into engagement with the sprocket wheel, means for holding said clutch into engagement during one revolution of the sprocket wheel and then releasing the clutch, and means then operating to throw the clutch on the sleeve into engagement with the sprocket wheel to thereby cause the actuation of the feed operating shaft and feed shaft.

- to cast material into the former, a feed operating shaft extending parallel to the main shaft and operatively engaging with said feed shaft, means for operatively engaging 5 said sleeve with the feed operating shaft, manually operable means for throwing the first-named clutch into engagement with the sprocket wheel, means for holding said clutch into engagement during one revolution 10 of the sprocket wheel and then releasing the clutch, means then operating to throw the clutch on the sleeve into engagement with the sprocket wheel to thereby cause the actuation of the feed operating 15 shaft and feed shaft, and means for holding the sleeve from rotation when its clutch is out of engagement with the sprocket wheel.
13. In a shock forming machine, oppositely disposed rails pivoted for movement 20 from a horizontal to an inclined position, oppositely disposed bearings mounted upon the rails, a shock former having trunnions extending into said bearings, angularly related arms mounted upon one of said trunnions, the free end of one of said arms being formed with a crotch, a link pivotally connected to the outer end of the other arm, a rod pivotally connected to the end of said link and extending to the forward end of 25 the machine, the crotched arm being adapted to engage in one position at the joint between said link and rod to thereby cause 30
- the joint to break, means for tipping the rails, means for simultaneously shifting the bearings forward upon the rails, and means 35 at the forward end of the machine engaging the said rod and resisting the movement of the rod to thereby cause the rotation of the shock former to a shock discharging position. 40
14. In a shocking machine, a supporting frame, a shock former rotatably mounted upon the frame, means for tipping the former to a shock discharging position, and means for causing a greater or less rotation 45 of the shock former depending upon the longitudinal inclination of the ground over which the machine is moving. 50
15. In a shocking machine, a shock former rotatably mounted for movement from a horizontal to a vertical position, means for causing a rotation of the shock former from a receiving to a discharging position, and means controlled by the lateral inclination 55 of the ground to cause a greater or less depression of one side of the former relative to the other side.

In testimony whereof I hereunto affix my signature in the presence of two witnesses.

HANS MUMM.
